Des. 234,465
Patented Mar. 11, 1975

234,465

INCENSE BURNER

Louis C. Warner, 205 Summit E., Apt. 302,
Seattle, Wash. 98102

Filed May 13, 1974, Ser. No. 469,379

Term of patent 14 years

Int. Cl. D31—00

U.S. Cl. D23—78

FIG. 1

FIG. 2

FIG. 3

FIG. 4

FIG. 5

FIG. 6

FIG. 1 is a perspective view of an incense burner showing my new design;

FIG. 2 is an elevational view thereof;

FIG. 3 is an elevational view taken at substantially 180° to that of FIG. 2;

FIG. 4 is a top plan view of the base portion of the incense burner of FIG. 1;

FIG. 5 is a bottom plan view thereof; and

FIG. 6 is a sectional view taken substantially on broken line 6—6 of FIG. 4.

The upright portion of the claimed burner has been omitted in FIGS. 4 and 6 for clarity of disclosure.

I claim:

The ornamental design for an incense burner, as shown.
